UNITED STATES PATENT OFFICE.

JAMES G. B. MANSFIELD, OF GORDA, CALIFORNIA.

SIDEHILL GANG-PLOW.

1,221,764.

Specification of Letters Patent.

Patented Apr. 3, 1917.

Application filed August 16, 1916. Serial No. 115,176.

To all whom it may concern:

Be it known that I, JAMES G. B. MANSFIELD, a citizen of the United States, residing at Gorda, in the county of Monterey and State of California, have invented new and useful Improvements in Sidehill Gang-Plows, of which the following is a specification.

This invention relates to a side hill gang plow.

One of the objects of the present invention is to provide a gang plow particularly adapted for side hill work in which the mold boards and shares are reversible to permit turning of the plow at the end of a furrow and turning of the land toward the down hill side.

Another object of the invention is to provide a plow of the character described which is simple, substantial and cheap to manufacture, and so constructed and arranged that the movable parts of the plow are firmly and securely mounted.

Another object of the invention is to provide a structure which will permit the plows to automatically reverse when the plow frame is turned.

Further objects will hereinafter appear.

The invention consists of the parts and the construction and combination of parts as hereinafter more fully described and claimed, having reference to the accompanying drawing in which:—

Figure 1 is a plan view of the plow.

Fig. 2 is a side elevation of the same having one mold board broken away or removed to show its support.

Fig. 3 is a plan view of the plow, showing the position of the mold boards and supporting frames while making a turn.

Fig. 4 is an end view of Fig. 3.

Fig. 5 is an end view of Fig. 1.

Fig. 6 is a detailed view of a latch employed in locking the mold board against reversible movement.

Referring to the drawings in detail, A indicates in general a plow frame which in this instance is made in two sections 2 and 3. These sections are connected by means of a pair of cross-links 4 which are pivotally attached as at 5 to the respective frames.

Journaled in each frame section near the forward end is a crank axle 6, and mounted on each crank axle is a supporting wheel 7. Pivotal mounted as at 8 in an extension 9

formed at each end of the rear connecting cross link 4, is a block 10 which supports a rack 11 and a lever 12. The lower end of each lever is connected by a link 13 to the crank arm of the respective axles 6 and 60 pawls 14 engageable with the racks 11 permit the levers to be moved and locked in any position with relation thereto, thus providing a means for raising and lowering each supporting wheel with relation to its frame 65 independently of the other. Each frame has a goose-necked beam 15 on the lower end of which, as at 16, is a mold board 17 on the forward end of which is formed a share 18. The mold boards and shares provided 70 are double faced, and therefore permits the mold boards and shares to be swung about the pivots 16 to assume the position indicated in Fig. 5, or a reverse position when the plow is traveling in the opposite direction. Pivotal connecting each mold board is a U shaped cross bail or bar 19, and pivotally connecting the rear ends of the respective frames 2 and 3 is a cross bail 75 20. This bail is mounted directly above the bail 80 19, and means hereinafter to be described is provided for securing said bails together when the plow is traveling in either one direction or the other. Connecting the forward ends of the respective frames 2 and 3 85 is a draw bar 21, and slidably mounted on said draw bar is a shackle 22 to which the team is hitched. Connecting the shackle 22 with a pivotally mounted arm 23 is a pair of chains 24, and pivotally attached to the 90 cross links 4 is a rearwardly extending handle 25. Mounted on the lower end of the said handle beam in alignment with the cross bails 19 and 20, is a latch 26. The forward end of this latch is provided with a projection 95 27 which is adapted to engage bar 19 and secure it against lateral movement with relation to the bail 20, the latch being operated in any suitable manner by the pivotally mounted hand grip 28 and connecting 100 link 29.

In operation referring to Fig. 1, when the plow is working on the side hill and traveling in the direction of arrow *a* the frames 2 and 3 will assume the position shown in 105 Fig. 1. The shackle 22 will assume the dotted line position shown at 22^a. The line of pull is thus central with relation to the supporting wheels and the mold boards, and the soil thrown up when the furrow is cut is 110

always turned toward the downhill side. When the end of the furrow is reached, the operator first stops the team and backs it up a sufficient distance to relieve the pull on the shackle 22. This is then pulled by means of the lever 23 to the full line position indicated at 22 in Fig. 1. The latch 27 is next retracted by means of the grip 28 to release the bars 19 and 20 with relation to each other. The team is then turned around in the direction of arrow *b* to turn the plow as a whole to assume the correct position when traveling in the opposite direction. The turning of the plow as a whole by the pull of the team causes the frame 2 to swing with relation to the frame 3 about the cross-links 4, and in this manner causes it to assume a forward position with relation to the frame 3. The pressure of the soil against the mold boards at the same time causes these to swing downwardly about their pivots 16 and upon the opposite side to the reverse position and they are in this manner automatically turned to throw the soil toward the downhill side when traveling in the opposite direction. The releasing of the latch 26 permits the U shaped beam 19 to swing with relation to the cross-beam 20 when the mold boards are turned, but the bails are again locked with relation to each other by the latch the moment the mold boards have been completely reversed. The team may then again be started and the next furrow cut.

The adjustable mounting of the supporting wheels 7, permits these to be raised and lowered and to act alternately either as a furrow wheel or as a land-side wheel. It can furthermore be seen that the pivoted mounting of the racks 11, together with the levers 12 mounted thereon, permits one crank axle to swing ahead when one frame swings ahead of the other. The angular position of the cranks is therefore changed while the vertical adjustment remains constant, unless changed by changing the position of the levers 12. The lever 23 provided with connected chains 24, is merely used for pulling the shackle from one end of the draw bar to the other, in turning, it otherwise remains stationary and maintains one chain taut while the other is slack. The pivotal connection of the cross-links 4 always permits one frame to advance with relation to the other when making a turn, this being of great importance as it permits the mold boards to automatically turn or reverse when the frames are turned.

The whole construction shown is simple, substantial, and cheap to manufacture, and so arranged that the movable parts of the plow are firmly and securely mounted, and practically any depth furrow may be secured.

65 The materials and finish of the several

parts of the plow may be such as the experience and judgment of the manufacturer may dictate.

I wish it understood that various changes in form, proportion and minor details of construction may be resorted to within the scope of the appended claims, and that I do not wish to limit myself to the specific design of construction here shown.

Having thus described my invention, 75 what I claim and desire to secure by Letters Patent is:—

1. In a side hill gang plow, a pair of movably connected frames, a reversible combined mold board and plow share on each operable by contact with the soil on turning the frames, and a draft-operated means for relatively moving the frames to position one share with its mold board in advance of the other. 80

2. In a side hill gang plow, a pair of movably connected frames, a reversible mold board and plow share on each operable by contact with the soil on turning the frames, a movably mounted wheel on each frame, 90 and means for shifting the wheels relative to their respective frames on relative movement between the latter. 85

3. In a side hill gang plow, a pair of plow share supporting frames, cross links connecting the same for relative movement, one of said links extending beyond the frames at each end, a block pivoted on each end of said link, a rack on each block, a lever coöoperating with each rack, a crank 100 axle journaled in each frame, wheel on each axle, and links connecting the axles to the levers. 95

4. A side hill gang plow comprising a pair of pivotally connected frames, a mold-board and share reversibly mounted adjacent the rear end of each frame, and means adjusting the wheels relative to the frames by and during relative movement between the frames, an adjustable supporting wheel 105 mounted near the forward end of each frame. 110

5. A side hill gang plow comprising a pair of frames, cross-links pivotally connecting said frames, a mold-board and share 115 reversibly mounted adjacent the rear end of each frame, a pivotally mounted cross bail connecting the mold boards, a second cross-bail pivotally connecting the rear ends of the frames, and means for securing said cross bails against movement with relation to each other. 120

6. A side hill gang plow comprising a pair of frames, cross-links pivotally connecting said frames, a mold-board and share 125 reversibly mounted adjacent the rear end of each frame, a supporting wheel mounted near the forward end of each frame, a pivotally mounted cross-bail pivotally connecting the mold-boards, a second cross bail pivot- 130

- ally connecting the rear ends of the frames, and a latch for locking the bails together against movement with relation to each other.
- 5 7. In a side hill gang plow, a pair of plow share supporting frames, cross links connecting the same for relative movement, one of said links extending beyond the frames at each end, a crank axle journaled in each 10 frame, wheels on the axles, and adjustable connections between the axles and the projecting ends of said link.
8. In a side hill plow, a wheeled supporting structure, a pair of reversible plow 15 shares and mold boards freely pivoted thereon for being reversed by contact with the soil in turning the structure, and means connecting the shares and mold boards for unity of movement.
- 20 9. In a side hill plow, a supporting structure, a pair of reversible combined plow shares and mold boards relatively movable to assume positions one in advance of the other, a pair of wheels swingingly mounted on the structure, and means for swinging the 25 wheels relative to the structure by and during shifting movement of the plow shares and mold boards.
10. In a side hill plow, a frame, shiftable wheels supporting the same, a reversible 30 share and mold board, means freely pivoting the share and mold board to the frame whereby the share will be automatically reversed by contacting with the soil in turning the frame and means for shifting the wheels 35 during the turning of the frame.

In testimony whereof I have hereunto set my hand.

JAMES G. B. MANSFIELD.
